United States Patent Office

Des. 227,983
Patented July 31, 1973

227,983

SNAP-ON CASING OR SIMILAR ARTICLE

Joseph N. La Borte, Baton Rouge, La., assignor to Ethyl
Corporation, Richmond, Va.

Filed Dec. 22, 1971, Ser. No. 211,152

Term of patent 14 years

Int. Cl. D25—01

U.S. Cl. D13—6

FIG. 1.

FIG. 2.

FIG. 1 is a perspective view of a snap-on casing or similar article embodying my new design, and

FIG. 2 is a sectional view taken along line 2—2 of FIG. 1.

I claim:

The ornamental design for a snap-on casing or similar article, substantially as shown.
